US00D965671S

(12) **United States Design Patent** (10) **Patent No.:** **US D965,671 S**
(45) **Date of Patent:** **** Oct. 4, 2022**

(54) **BINOCULARS TRIPOD ADAPTER**

(71) Applicant: **SHENZHEN YOKEHUWAI TECHNOLOGY CO., LTD.**, Shenzhen (CN)

(72) Inventor: **Hongwei Huang**, Zhuhai (CN)

(73) Assignee: **SHENZHEN YOKEHUWAI TECHNOLOGY CO., LTD.**, Shenzhen (CN)

(**) Term: **15 Years**

(21) Appl. No.: **29/764,396**

(22) Filed: **Dec. 30, 2020**

(51) LOC (13) Cl. **16-05**

(52) U.S. Cl.

USPC **D16/245**

(57) **CLAIM**

The ornamental design for a binoculars tripod adapter, as shown and described.

DESCRIPTION

FIG. 1 is a perspective view of a binoculars tripod adapter showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the binoculars tripod adapter that form no part of the claimed design.

1 Claim, 8 Drawing Sheets
